(57) **CLAIM**

I claim the ornamental design for an electronic control device, as shown and described.

DESCRIPTION

FIG. 1 is a front view showing my new design;
FIG. 2 is a rear view thereof;
FIG. 3 is a top view thereof;
FIG. 4 is a bottom view thereof;
FIG. 5 is a right side view thereof;
FIG. 6 is a left side view thereof; and,
FIG. 7 is a perspective view thereof.
